 American Can Company, New York, N. Y., a
 corporation of New Jersey

Application September 28, 1939, Serial No. 296,982

1 Claim. (Cl. 221—62)

The present invention relates to dredging cans for powders, condiments and the like and has particular reference to a fully sealed rectangular can which is opened by breaking out scored parts cut in a particular or predetermined position within a sunken panel of the can end to provide a slide seat for a flat perforated top slide, two opposed edges of which engage under ledges formed in bent and collapsed side walls of the sunken panel by means of which the can may be fully opened for dispensing of its contents as in removal by a spoon, or the dispensing may be done by sifting the contents through the perforations or dredge openings in the slide, or the can may be reclosed again against any discharge of its contents.

An object of the present invention is the provision of a dredging can which is initially sealed on its contents and which may be opened to make effective a flat perforated slide which is slidably retained in a sunken panel part of the can top, the position and style of opening as well as the combined cooperation of the parts allowing for selective full open dispensing or sifter dispensing of the can contents or for reclosing the can.

Another object is the provision of a flat slide member for a rectangular dredging can of the character described which is slidably retained on the top of the can by folded ledges formed in the top and which in one position exposes a large dispensing opening made in the can top at the time the can is first opened, thus permitting a large amount of the contents to be removed as by a spoon and with only a slight movement, the slide member covers the dispensing opening and recloses the can, an intermediate position of the slide providing for sifter dispensing of the contents.

Numerous other objects and advantages of the invention will be apparent as it is better understood from the following description, which, taken in connection with the accompanying drawing, discloses a preferred embodiment thereof.

Referring to the drawing:

Figure 1 is a perspective view of the upper part of a can embodying the present invention and showing the can closed;

Figs. 2, 3 and 4 are top plan views of the can of Fig. 1 showing the slide closure in a different position in each view; and

Figs. 5 and 6 are longitudinal and transverse sectional views drawn to a larger scale and taken

respectively along the lines 5—5 and 6—6 in Fig. 4.

The present invention is concerned with a dredging can having a simple one-piece top slide which has longitudinal movement across a depressed panel wall, the slide being held in position by overhanging ledges formed in the can end and on opposite sides of the depressed panel part. The slide becomes effective after the can has been initially opened by breaking out a scored part of the top end. Such a can is rectangular in shape and the slide is also rectangular so that it may be moved back and forth across the can top while being guided and maintained in a straight line of travel to perform the proper action for dispensing of the contents or to act as a reclosure for the opened can.

Such a rectangular can comprises a can body 11 preferably formed of metal. The invention is concerned primarily with the construction of the can top and parts carried thereby and therefore only the can top is shown in the drawing. It will be understood that the can will have an imperforate bottom of usual construction. A top or end member 12 is provided and may be primarily of the usual dished form required for double seaming where the end 12 and the can body 11 are joined together in a double seam the seam being designated by the numeral 14. This usual dished form of can top leaves a web wall 15 inside of the surrounding double seam and this wall in the present embodiment is further depressed in a sunken panel 16. The panel 16 is rectangular, its walls following the general rectangular contour of the walls of the can top, the panel part being of slightly smaller dimensions to completely confine the slide closure member previously referred to.

The sunken panel 16 as it is primarily drawn from the web wall 15 of the can end, is formed with a flat panel wall 17 and surrounding vertical walls 18. Walls 18 are boundary walls joining the panel wall with the top end wall 15. Two of the walls 18 are later reshaped as hereinafter described. The flat surface of the sunken panel wall 17 permits the use of a flat one-piece top slide 21 which rests in close contact with the panel wall but has movement over the wall while still at all times closely engaging with its upper surface.

To insure simple and effective sliding connection for the slide member 21 and at the same time to retain it against displacement from the can top 12 in its various positions, two opposite walls 18 of the sunken panel 16 are collapsed

into an S-shape in cross section as indicated at 22 in Fig. 6. Each reformed collapsed wall 22 now consists of a straight channel 23 and a straight overhanging ledge 24. There are thus two opposed channels and two opposite overhanging ledges.

From a manufacturing standpoint it is desirable to assemble the slide 21 in the sunken panel 16 of the can top 12 prior to collapsing the walls 18 in forming its channels and ledges 23, 24. This means, therefore, that the slide 21 is in seated position on the sunken panel 16 at the time of forming the S-section 22 in the opposed walls of the panel. It will thus be evident by reference to Fig. 6, that the slide 21 after reshaping of the walls is movably retained by having its opposite edges engaged within the channels 23, the overhanging ledges 24 preventing displacement of the slide from the can end.

The slide 21 is preferably in the position illustrated in Fig. 2 when the can, filled with its contents, is received by the ultimate consumer. This is an exact predetermined position, the forward edge of the slide, toward the left as viewed in this figure, being against one of the straight vertical walls 18 of the depressed panel 16. It is first necessary when access to the can contents is to be had, to effect an opening through the imperforate can top.

The can top 12 on one side of its median line and in one end of its sunken panel 17 is cut through fully or in part by score lines. These lines are preferably patterned as a continuous arc line 27 which has its ends joined by a broken scored chord line 28. Such score lines set off a removable part 29 of the can top.

As a preparatory step in opening the can, the slide 21 is drawn longitudinally across the can top to the opposite side, that is, from the position of Fig. 2 into that of Fig. 3. To permit easy movement of the slide, the same may be previously formed with a central looped finger-piece 31, which in the embodiment herein disclosed, is formed centrally of the slide and which extends substantially across its width. Such a finger-piece being an integral part of the slide, requires no additional parts. Its top is below the top rim of the surrounding double seams 14, as best illustrated in Fig. 5. This allows for stacking or other handling of the cans.

With the slide 21 in the position of Fig. 3, the scored lines 27, 28 are fully exposed and may be easily broken through. To open the can and to render the slide 21 effective as a slide closure, the segmental removable area or part 29 is pushed down or depressed into the can, the arcuate score line 27 breaking through and the metal of the top end bending along the broken chord score line 28.

This removal of the part 29 from the plane of the can top creates a dispensing opening 32 (Fig. 5). The shape of this opening in this present embodiment is such as to allow for insertion of a spoon into the can. The straight chord part 28 of the opening provides a scraping surface so that a spoonful of the contents of the can may be withdrawn when the parts are in this open position.

In order to reclose the opened can and to

confine the contents again, the finger-piece 31 of the slide 21 is again engaged and the slide is pushed back to its original position. Fig. 2 illustrates the slide with its forward edge against the end wall 18 of the sunken panel 16 as it was before opening of the can. The slide in this position fully covers the dispensing opening 32 and closes off the can against inadvertent dispensing of its contents.

The sifting position of the slide 21 is disclosed in Fig. 4. This is an intermediate position the opposite edges of the slide being free and spaced from both straight walls 18 of the panel 16. In the present embodiment of the invention, the drawing discloses an arcuate or curved line of perforations 35. In the sifter position of Fig. 4, these perforations are aligned and in registry with the dispensing opening 32. As illustrated in Fig. 5 these dispensing openings are cut entirely through the slide wall and they thus form passageways for the contents in conjunction with the dispenser opening 32. The contents passing out through the perforations are thus subjected to a sifter or dredging dispensing action.

By reason of the construction of the finger-piece 31 and its being formed from the bent-up central section of the slide, an inwardly curved depression 36 is formed at the base of the finger-piece. In the intermediate or sifting position of the slide this is utilized for holding the slide in its sifting position. For this purpose a small protuberance 37 (Figs. 2 and 5) which is pressed up in the panel wall 17 centrally of the can top, is engaged into the depression 36 at the base of the finger piece 31. This removably holds the slide in exact sifting position.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A rectangular dredge top can comprising a top and having a depressed panel provided with a dispensing area and an outward protuberance spaced therefrom, a perforated slide member movably confined in close sliding contact with said panel and movable in opposite directions thereon relative to said area, said slide having an integral upstanding looped finger engaging element thereon and a consequent curved depression on its panel engaging surface directly beneath said finger element, movement of said slide member in one direction relative to the panel covering said dispensing area and in the opposite direction exposing said area, said slide when in an intermediate position aligning its perforations with said dispensing area for a sifting of the can contents, at which time said panel protuberance releasably engages said slide depression to yieldably maintain the slide in sifting position.
